[57] CLAIM

The ornamental design for a spacecraft simulator for an entertainment system, as shown and described.

DESCRIPTION

FIG. 1 is a top plan view of a spacecraft simulator for an entertainment system showing our new design;

FIG. 2 a rear elevational view of said spacecraft;

FIG. 3 a left side elevational view of said spacecraft;

FIG. 4 a right side elevational view of said spacecraft;

FIG. 5 a front elevational view of said spacecraft;

FIG. 6 a bottom plan view of said spacecraft; and,

FIG. 7 is a reduced left side perspective view of said spacecraft, the broken line showing of support base is for illustrative purposes only and forms no part of the claimed design.
